UNITED STATES PATENT OFFICE.

FRANK N. L. WILLETT, OF AURORA, ILLINOIS.

SHEEP SHEARS.

Application filed July 19, 1920. Serial No. 397,319.

To all whom it may concern:

Be it known that I, FRANK N. L. WILLETT, a citizen of the United States, residing at Aurora, in the county of Kane and State of Illinois, have invented certain new and useful Improvements in Sheep Shears, of which the following is a specification, reference being had to the accompanying drawings, and to the reference characters marked thereon, which form a part of this specification.

This invention relates to an improvement in animal shears and has for its object to provide improved means for preventing wear of the parts and thus obviating frequent replacement.

Sheep shears on the market at the present time are generally of the construction illustrated in my prior Patent No. 896,497, of 20 August 18, 1908, and the patent to Bartlett, No. 1,301,089, dated April 22, 1919, and embrace a vibrator fulcrumed upon a pivot post,—the vibrator carrying movable cutters. One serious objection to the pivot post construction lies in the fact that the wear between the parts is not even and affects the contact of the movable cutters over the comb or fixed cutters, necessitating constant adjustment of the movable cutter 25 with respect to the fixed cutter. Presently this irregularity between the fixed pivot post and the vibrating arm carrying the cutters becomes so serious as to necessitate renewal of the parts constituting the fulcrum. Such renewals, in sheep shearing season, are frequently made every two or 30 three days.

In that form in which I have chosen to illustrate my invention, Fig. 1 is a top plan 40 view of a conventional sheep shears embodying my invention.

Fig. 2 is a central, vertical, longitudinal, sectional view thereof.

Fig. 3 is a group view of four parts constituting the fulcrum mechanism.

Fig. 4 is a vertical, sectional view of a detail showing the fulcrum arrangement of the said Bartlett Patent No. 1,301,089.

The sheep shears illustrated comprise a 50 handle or casing 1, having a removable cover 2, held in place by means of a screw or screws 3. The cover is provided at its

outer end with a hood or dome portion 4 in which is housed the tensioning or adjusting device indicated generally at 5. The adjusting device forms no part of the present invention and need not be further described. It will be apparent, however, that it bears upon the outer portion of the vibrating arm that carries the cutter blades.

Within the casing 1 is mounted a sleeve 6, longitudinally apertured, centrally, to provide a journal bearing for a drive shaft 7. The inner end of the sleeve 6 has screw threaded connection with the casing 1 and is secured thereto by a set screw 3. The outer end of the sleeve 6 is provided with an annular flange 8 which bears against the shoulder 9 of a rotatable sleeve or bushing 10, interposed between the fixed sleeve 6 and the casing 1. The fixed sleeve 6 is of different diameters as shown in Fig. 2. The casing 1 has an interior annular shoulder 11 against which the inner end of the rotating sleeve or bushing 10 and the shoulder 12 of the fixed sleeve will bear. The sleeve 6 has two oil holes, 13, 14, the latter communicating with the oil chamber 15 in the casing 1. Access to the oil chamber 15 will be had through the casing aperture shown as closed by the screw plug 16. The oil hole 13 is in that part of the sleeve 6 which is within the rotating sleeve 10.

At its inner end, the drive shaft 7 is provided with a crank disc 17 having a crank pin 18. This crank pin is connected with the inner forked end 19 of the vibrator or vibrating arm 20; the crank pin 18 being inserted between the arms of the fork and moving between the same when the shaft 7 is rotated to operate the vibrator. The vibrator 20 is fulcrumed upon a pivot post and when caused to vibrate about said fixed post, will operate the movable cutter 21 carried thereby. The cutter 21 cooperates with the fixed cutter or comb 22, which latter is removably secured to the casing 1 as indicated at 23.

The outer end of the rotatable bushing 10 is provided with an enlarged part 21 rotatable in the casing, to form one of the members of a joint. The other member 25 of the joint, is connected to the housing 26 of an operating shaft 27 which shaft is actuated

by some suitable source of power. The operating shaft 27 is provided with a suitable driving gear 28 which intermeshes and engages with a complementary driving gear 5 mounted upon the outer end of the shaft 7. The operation of the parts thus described is familiar to those skilled in the art and need not be further explained.

The fulcrum arrangement for the vibrating arm 20 comprises the following construction: A fulcrum pin, designated as a whole by the letter F (Fig. 3) comprises the pin proper, 30, provided with a screw threaded plug 31, with an intermediate shoulder 32. The plug 31 is screw threaded through a suitable aperture in the casing 1 and locked in said position by the nut 34. A washer 35 is placed over the fulcrum pin 30 and rests upon the shoulder 32. An anti-friction, hemispherical member 36, provided with a central vertical aperture 37 is placed over the fulcrum pin 30, its lower surface being straight, rests directly upon the washer 35.

The vibrating arm 20 is provided with an interiorly screw threaded aperture 38 to receive a bearing plug 39. In the under surface of the plug 39 is a recess 40 complementary to the exterior surface and shape of the hemispherical member 36. This recess 40, of course, may be formed directly in the under side or face of the vibrator arm 20, in which case, the plug 39 will not be used. It will be understood, therefore, that when the vibrating arm 20 is in operative position, the several parts shown in Fig. 3 will appear assembled as indicated in Fig. 2.

The oscillation of the arm 20 about the pin 31 will cause the member 36 to slightly rotate about the fulcrum pin 30 and the washer 35 will also slightly rotate. Suitable lubrication between the bearing surfaces of the member 36 and the recess 40 will be afforded through an oil hole 41.

Referring now more particularly to the prior art construction illustrated in Fig. 4,—A represents the housing member corresponding to the casing 1; B the vibrating arm corresponding to the arm 20; and C a screw threaded fulcrum plug held to the housing A by the nut D and provided with an antifriction spherical top E, resting in a suitable recess R in the under side of the plug P. This recess is somewhat tapered, provided with a rounded bottom, complementary with the spherical head E of the fulcrum plug C. When the vibrating arm B oscillates back and forth about the fixed plug C, the contacting surfaces between the plug P and the spherical end E grind and wear away so that flat portions appear. This end E soon becomes no longer spherical.

The result of this wearing away of the end of the fixed plug due to the rapid motion of the vibrating arm B in the prior construction of the device is that the spherical

tions now on the market, as already stated, so changes the adjustment of the forward and operating end of the vibrating arm B as to impair the efficiency of the cutting operation and of the tension device. The result is that the plug P and the fulcrum pin C have to be constantly renewed and very seldom last during more than two or three days of shearing.

The improved fulcrum construction shown in Fig. 2, I have used continuously in shearing several thousands of sheep without impairing the effective tension contact of the cutter blades 21, 22 and without renewal of the parts. In fact, after using my improved fulcrum construction in the shearing of several thousands of sheep, I have found that the wear between the shoulder 32 and the washer 35, between the washer 35 and the hemispherical member 36, and between the latter and the plug 39, has been negligible, and such wear as did take place only served to make the parts fit together and operate more perfectly.

In the construction shown in Fig. 4, lubricant placed in the aperture G would not find its way into the bearing recess of the plug P and around the spherical head E of the fulcrum pin C for the reason that the tension device 5 pressed the plug P and the spherical head E of the fulcrum pin C so firmly together as to prevent lubrication. In my device, as illustrated in Fig. 2, the vibration of the arm 20 tends to shift the hemispherical member 36 and turn it in a horizontal plane about the axis of the fulcrum pin 30. This shifting of position has the effect of working the lubricant from the aperture 41 down over the outer surface of the member 36, so that said outer surface and the interior contacting surface of the recess 40 do not grind upon each other but are at all times properly lubricated.

In prior constructions, the friction between the rotatable bushing 10 and the fixed sleeve 6 has caused considerable trouble and expense. Lubricant in the oil chamber 15 finds its way through the oil hole 14 to the shaft 7 throughout its length, but because of the shoulders 11, 12, does not normally pass to the inner surface of the rotatable bushing 10. Hence I have provided as an improvement the oil aperture 13. By so doing, the oil will gradually collect therein from the shaft 7 and then pass between the sleeves 6 and bushing 10 and keep their bearing surfaces properly lubricated. This is a very important feature.

It will be seen that my device is simple in construction, easily assembled and will last indefinitely,—that is, as long as the tool proper will last.

It will be understood, of course, that while I prefer to use the washer 35, the same may be omitted, since the under flat surface of

the hemispherical member 36 may rest directly upon the shoulder 32 of the fulcrum stud F.

I claim as my invention:

- 5 1. A fulcrum for sheep shears comprising a support and a vibrating arm provided with a rounded recess on its lower surface, in combination with a fulcrum stud on said support and extending into said recess, and a bearing member rotatably mounted on said stud and resting on said support, said bearing member having an upper portion located in said recess and shaped to conform to the curvature of the latter.
- 10 2. A fulcrum for sheep shears comprising a support and a vibrating arm in combination with a fulcrum stud on the support, an opening through the arm, an apertured plug removably mounted in said opening and having a hemispherical recess in its under side, and a bearing member rotatably mounted on the stud and resting on said support and having its top complementally shaped to enter the plug recess.
- 15 3. A fulcrum for sheep shears comprising in combination with a support and a vibrating arm, a fulcrum stud vertically mounted in the support and having a horizontally arranged circumferential shoulder, a washer on the stud-shoulder, an interiorly threaded opening through the vibrator arm, an exteriorly threaded plug removably located in said opening, said plug having on its under side a hemispherical recess and
- 20 35 an axial aperture through its top in communication with the recess, and an aper-

tured bearing member rotatably mounted on the stud, said member being hemispherical on its top to engage the plug recess and flat on its bottom to bear on the washer.

40

4. The improvement in sheep shears comprising a casing having an annular interior shoulder, a shouldered sleeve fixed in the casing with its shoulder in contact with the casing shoulder, a rotatable shaft in the sleeve, a bushing rotatably mounted between the sleeve and the casing in rear of the aforesaid casing shoulder, an oil chamber in the casing forward of its shoulder, an aperture through the sleeve forward of its shoulder and in communication with the oil chamber, and a second aperture through the sleeve in rear of its shoulder and connecting the interior shaft bearing surface with the exterior bushing bearing surface.

45

5. In a sheep shears, a casing, a sleeve fixed therein, a shaft rotatable in said sleeve, an oil chamber in the casing, means for directing oil from said chamber to said shaft, a rotatable sleeve within the casing and surrounding one part of the first mentioned sleeve, and an oil passageway in the first mentioned sleeve connecting the shaft with the inner surface of the rotatable sleeve.

50

In testimony that I claim the foregoing as my invention I affix my signature, in the presence of two witnesses, this 10th day of July, 1920.

FRANK N. L. WILLETT.
